(57) CLAIM

The ornamental design for a sofa table, as shown and described.

DESCRIPTION

FIG. 1 is an upper perspective view of the sofa table showing my design.

FIG. 2 is a front view thereof;

FIG. 3 is a back view thereof;

FIG. 4 is a side view thereof;

FIG. 5 is an opposite side view thereof;

FIG. 6 is top view thereof; and,

FIG. 7 is another perspective view, showing an open position.

The bottom of the table forms no part of the claimed design.
